UNITED STATES PATENT OFFICE

2,202,561

WINDOW HOLDER

**Eugene A. Lahiere, Princeton, N. J., and Thomas
Gillmet, Faust, N. Y.**

Application April 25, 1938, Serial No. 204,194
Renewed August 7, 1939

2 Claims. (Cl. 292—238)

This invention relates to an improved window holder and seeks, among other objects, to provide a device of this character which, when attached to a window casing, will permit the window to be raised without interference but which, after the window has assumed a desired raised position, will automatically engage a portion of the window for holding it in the desired raised position.

Another object of the invention is to provide
10 a window holder employing a frame which will
prevent the window-engaging element from in-
jury and will guide said element into and out of
operative position.

A further object of the invention is to provide 15 a device of this character wherein means are provided on the frame for limiting too great rearward movement of the window-engaging element.

As a still further object, the invention seeks to provide a window holder which may be positioned on a window frame in such a manner that the window-engaging element employed may be shifted to a position for locking the window and permitting unauthorized raising thereof.

25 A still further object of the invention is to provide a window holder which will be effective for preventing rattling of a window sash in a window frame.

frame. A further object of the invention is to provide a device of this character which is characterized by utmost simplicity of construction and ease in operation.

Other objects of the invention not specifically mentioned hereinabove will become apparent during the course of the following description.

35 Our invention is illustrated in the accompanying drawing, wherein

Figure 1 is a vertical sectional view of a window casing showing in elevation, our improved window holder as it will appear thereon and in locked position against a raised window sash.

Figure 2 is an enlarged side elevation showing the window holder in engagement with a portion of a window sash, the out of engagement position being shown in dotted lines.

45. Figure 3 is an enlarged perspective view of our improved window holder and showing the combination pivot and mounting bolt as it will appear before insertion through the frame, and

Figure 4 is an enlarged side elevation showing our improved device as it will appear when inverted and used as a lock.

Referring now more particularly to the accompanying drawing wherein similar reference numerals will be seen to indicate like parts throughout the various views, the numeral 1 indicates

in general a window frame having a sill 2 and a side member 3. Slidably mounted in the window frame 1 are sashes 4 and 5 which are of any desired construction and include side rails 6.

In carrying our invention into effect, we employ a frame which is shown in general at 7. The frame includes an oblong base plate 8 which is adapted to be fastened to the side member 3 by means of screws 9 and 10. The frame 7 is formed from a single piece of sheet metal and is reduced and bent at its rear edge to define a right angularly disposed rear stop wall 11, and said wall 11 has formed thereon a reduced downwardly inclined ear 12 which lies in parallel spaced relation to the plate 8 and defines a bearing 13. 5 10 15

Fig. 13. Swingly mounted in the frame 7 is an engaging element shown generally at 14. The engaging element is preferably formed of rubber of the semi-hard variety. The engaging element is formed with a front wall 15 which is curved at its upper end portion to define a cam 16. The curved wall is projected rearwardly and defines at its rear terminus a rib-shaped stop 17 which, as best seen in dotted lines in Figure 2, is adapted to abut the stop wall 11 when the device is in inoperative position. In that position, as will be noted, the wall 15 is disposed in parallel relation to the front edge of the plate 8. The engaging element 14 is provided with a curved rear wall 18 having an opening 19 therein which is adapted to receive therethrough a bolt 20. As will be clearly understood from a scrutiny of Figures 2 and 3 of the drawing, the bolt 20 extends through the bearings

13, through the opening 19, and through an aligned opening in the plate 8. The bolt is, of course, screwed into the side member 3 of the window casing or frame and said bolt, therefore, serves to mount the device on said casing in the most rigid manner possible. That is to say, the bolt 20 serves a two-fold function in that it pivotally mounts the element 14 between the plate 8 and the ear 12 and, at the same time, said bolt assists in securing the device in a properly installed position on a window casing. The metal employed in the manufacture of the frame 7 is of suitable thickness so that enough strength will be present to resist too great inward movement of the bolt 20. Therefore, danger of forcing the ear 12 against the face of the element 14, with consequent clamping of said element, will be prevented.

Although the operation of the invention as described thus far is believed to be clear, a short further description is thought not to be out of 55

order. After the device has been installed on the window casing or frame, and the sash, for example, the sash 4, is raised, the element 14 will swing slightly to the rear, that is to say, toward the position shown in dotted lines in Figure 2, and will not impede the raising movement of the sash. After the sash has been raised to the desired position, the sash is released and the engaging element 14 will rock forwardly automatically and will engage the cam face 16 with the side rail 6 of the sash, for effectually holding the sash in the desired position. In order to release the element and permit the sash to slide downwardly toward closed position, it is only necessary to engage the lower end portion of the curved wall 8 of said element and urge the lower end portion of the element inwardly, when the cam surface 16 will be rocked away from the rail 6 for freeing the sash.

As shown in Figure 4 of the drawing, it is possible to employ our improved window holder for locking the window against raising movement. When the invention is used in this manner, it is mounted on the window frame in inverted position, that is to say, in a position inverted with respect to that in which the device is mounted when being used merely as a holder. The cam surface 16 will be engaged, in locked position, to the lower rail of the sash and will prevent raising thereof. In order to insure proper locking, the element 14 is swung rearwardly, which swinging movement is accomplished by manually engaging the upper end portion, shown at 21, of said element and shifting said upper end portion in the direction of the arrow. Shifting of the portion 21 in the opposite direction will, of course, release the element and permit raising of the window. The use of this embodiment of the invention is particularly efficacious for the reason that the device will prevent unauthorized raising of the window by burglars or thieves. Moreover, when the device is in locked position, the window will be prevented from rattling. It is thought that further description of our invention is unnecessary.

Having thus described the invention, what is claimed as new is:

1. In a window holder, a frame adapted to be positioned on a side rail of a window and including a mounting plate projected to form a stop wall, said stop wall being projected in overhanging relation to define an ear, said mounting plate having openings to receive fastening devices whereby the window holder may be secured to the side rail, an engaging element carried by the frame between the ear and the mounting plate and within the confines of the frame when said element is in inoperative position, and means mounting the engaging element in the frame for pivotal movement, said means also aiding in securing the device to the side rail, said engaging element having a straight front wall curved at one end to define a camming surface engageable with a portion of a window sash for holding said sash in a fixed position and against downward movement, said front wall permitting free raising of the sash, said element having a rib engageable with the stop wall in retracted position, said stop wall limiting too great rearward movement of the element. 5 10 15 20

2. In a window holder, an engaging element formed of semi-resilient material and being of substantially diamond shape, said engaging element having a straight front wall curved at one end portion to define a cam face and being formed with a rear wall having a curved upper portion, said curved portion of the front wall and the 30 curved upper portion of the rear wall meeting to define a rib shaped stop, said rear wall having a slightly inwardly curved lower portion cooperating with the straight front wall to define a manually engageable portion, and means for mounting 35 the element on a side of a window sash so that the cam face will be automatically engaged with the side rail for limiting downward movement of the sash, said manually engageable portion being shiftable for confronting the straight front 40 wall of the element with the sash for freeing said sash. 45
